ERNEST R. GIPPERT, OF NEW YORK, N. Y., ASSIGNOR TO ATLAS DEVICES COMPANY, INC., A CORPORATION OF NEW YORK.

CARRIER FOR PNEUMATIC-DISPATCH-TUBE SYSTEMS.

Application filed October 24, 1921. Serial No. 509,773.

To all whom it may concern:

Be it known that I, ERNEST R. GIPPERT, a citizen of the United States, residing at New York, in the county of Bronx, State of New York, have invented certain new and useful Improvements in Carriers for Pneumatic-Dispatch-Tube Systems; and I do hereby declare the following to be a full, clear, and exact description of the invention, such as will enable others skilled in the art to which it appertains to make and use the same.

This invention relates to carriers for pneumatic dispatch tube systems and involves particularly the provision of an improved form of buffer head for the carrier.

Carriers are provided with buffer heads made of resilient material, usually felt, which serve both to provide means against which the air pressure in the line for driving the carriers is exerted, the heads acting as pistons, and also to absorb the shock due to impact between the carriers and the walls of the transit tubes when encountering bends in the latter, and when striking valve doors or flaps during the passage of the carrier through the transit line and its discharge therefrom. Furthermore, when the carrier is discharged from the line the buffer heads serve to break the fall of the carriers into the discharge receptacle.

As heretofore constructed the buffer heads at the ends of carriers have been made of one piece of material, the material generally consisting of a closely compressed felt made in the form of a disc of substantial thickness, with more or less complicated means for fastening the buffer heads permanently in position. Due to wear the buffer heads must in time be replaced which, with the present forms, is a rather difficult operation and a costly one, due not only to the time and labor involved in detaching the buffer heads from the carrier shell, but also to the cost of material, for although the buffer head might only be worn near the outer ends, which is generally the case, yet the entire buffer head must be replaced.

The present invention provides a buffer head consisting of a plurality of separate pieces which are superimposed one upon the other and are provided with fastening means such that they may be separately detached one from the other and from the

carrier shell. The wear on the buffer head is taken up by the outer piece or pieces, that is the piece at the extreme outer ends of the head. When it becomes necessary, therefore, to restore the buffer head to its primary state of efficiency it is only necessary to detach such outer piece or pieces of the head as are worn to an extent requiring replacement, while the inner piece or pieces remain on the carrier. Since the outer worn piece or layer of the buffer head constitutes only a fractional part of the entire amount of material in the head a considerable saving is effected in replacement, since it has been found in practice that the inner pieces or layers are required to take so little of the wear on the head that they remain substantially intact and in good condition for an indefinite period of time.

In order to provide an air tight connection between the carrier and the inner walls of the transit tubes carriers are customarily fitted with flexible washers which are of slightly larger diameter than the diameter of the buffer head and also the inside diameter of the transit tubes. These washers are attached in different positions, in one form of construction the washer being attached to the end of the buffer head and in another being located between the buffer head and the shell of the carrier. In the buffer head constructed in accordance with this invention the flexible washer is positioned preferably between two of the pieces or layers of material comprising the buffer head. When the carrier is in flight through the transit tubes these flexible washers act as piston rings to provide a tight connection with the inner walls of the tubes thus preventing leakage of the propelling current of air past the carriers. Since the washer is of a diameter slightly larger than the inside diameter of the tubes, the outer edges thereof are bent backwardly, the washer of one head being bent toward the shell of the carrier and that of the other head being bent away from the shell depending upon the direction of travel and the position in which the carrier is inserted in the tubes. Opposed to the bending of the washers in a direction the reverse of the direction of travel is the force exerted by the propelling air current which tends to straighten out the curved outer edges and maintain the washer flat. The efficiency of the washer as a check to

prevent leakage is enhanced when the doubling back or bending of the outer edges thereof is reduced to a minimum. This result is nicely accomplished in the buffer head 5 of the present invention by providing a backing for the flexible washer consisting of the pieces or layers of the head between which the washer is held, these pieces being of a diameter sufficiently large so that they will provide a backing on both sides of the washer to support and stiffen it against curling or bending in one direction or the other. This support or stiffening is not attained in the present buffer head constructions as will be evident in the case where the washer is supported between the buffer head and the shell of the carrier, in which arrangement the washer depends for its support on one side on the shell of the carrier 20 which is of considerably less diameter than the buffer head; and also in the case where the washer is supported on the end of the buffer head in which arrangement it is totally without support on one side. In order to provide for a certain freedom of motion while maintaining the efficacy of the backing provided by the layers of the buffer head in this invention, the opposing faces of the pieces or layers, between which the washer is positioned, have rounded peripheral edges which provide an annular recess and a curved backing for the washer in either direction.

In the preferred construction the buffer head is made of two pieces or layers of material, an inner piece attached to the shell of the carrier and an outer piece superimposed upon the inner piece and provided with fastening means whereby it may be quickly detached for repairs or replacement. In this construction the pieces comprising the buffer head are of slightly larger diameter than the shell or body of the carrier and the flexible washer serving as a "piston ring," of larger diameter than the buffer head, is interposed between the pieces or layers comprising the latter.

The fastening means for the separate pieces comprising the buffer head are preferably arranged for quick detachment of the outer piece by securing the latter to the devices provided for fastening the inner piece to the carrier shell. This is accomplished by providing a screw member or members for securing the inner buffer piece to the carrier shell, and preferably secured by nuts inside of the carrier shell, each screw member having a shank portion provided with a threaded socket. The outer piece is fastened in superimposed relation to the inner piece by means of screws passing through the outer piece and which are adapted to enter the threaded sockets of the screw members holding the inner piece to the carrier shell.

The invention is illustrated in the accompanying drawing in application, as an example, to a carrier having two-piece buffer heads at its ends. In these drawings—

Fig. 1 is a view partly in section illustrating a carrier having two-piece end buffer heads and identifying devices set in recesses at the outer ends of the buffer heads; 70

Fig. 2 is a plan view of an end of the carrier with the numbering device removed to show fastening means for the upper piece of the buffer head; 75

Fig. 3 is a view along the line 3—3 of Fig. 1; and

Fig. 4 is a view along the line 4—4 of Fig. 1.

Referring to these drawings the carrier shell 5 consists of two telescoping sleeves such as the outer sleeve 6 and the inner sleeve 7, each being closed at one end as at 8 the end closure of the outer sleeve 6. These sleeves are secured together so as to be capable of relative rotation in a direction laterally of the carrier, and each has a cut away portion as at 9 in the outer sleeve 6, and 10 in the inner sleeve 7, by which the carrier may be opened and closed when the sleeves are rotated relative to each other in one direction or the other, as is common in the construction of carrier shells. 95

Secured to the closed end of each of the sleeves as at 8, the end of sleeve 6, is a buffer head 11 consisting of an inner piece 11^a and an outer piece 11^b, each of resilient material such as a closely compressed heavy felt of substantial thickness, and each being circular in form. The disc shape pieces 11^a and 11^b comprising the buffer head are of a diameter slightly less than the transit tubes of the pneumatic dispatch system and somewhat larger than the diameter of the shell 5 of the carrier. Interposed between the inner and outer pieces 11^a and 11^b in a flexible leather washer 12, the diameter of which is larger than the diameter of the buffer head 11 and which is also slightly larger than the diameter of the transit tubes to act as a "piston ring" for providing a substantially air tight connection between the carrier and the inner walls of the transit tubes. 110

The inner piece 11^a of the buffer head is secured to the end of the carrier shell 5 by means of a pair of screws 13 each having a head 14 provided with screw driver slots 15, a shank portion 16 provided with a threaded socket 17, and a reduced end portion 18. These screws pass through openings provided therefor in the felt, the reduced end portion 18 passing through the end wall 8 and a fastening nut 19, the latter consisting of a flat strip of metal having two threaded openings, one for each of the screws 13, and serving as a nut for both screws by which the inner piece 11^a is tight- 120 125 130

ened against the end of the shell. Interposed between the end wall 8 and the nut 19 is a disc 20 for reenforcing the end wall of the carrier shell by providing a double thickness of metal against which the buffer head is fastened.

The outer piece 11^b of the buffer head is provided with a circular depression 21 in which is a disc shaped bearing plate or washer 22 having a pair of counter sunk screw holes 23 therein for receiving the screws 24. The screws 24 pass through the upper piece and enter the threaded sockets 17 in the screws 13 thus providing fastening means by which the upper piece 11^b of the buffer head is firmly secured in superimposed relation to the inner piece 11^a and to the shell of the carrier. The depression 21 may be fitted with a numbering device for identifying the carriers, such as a disc 25 of paper or other suitable material imprinted with numbers and a celluloid protective disc 26 covering the paper disc.

The outer peripheral edges of the opposed faces or surfaces 27 and 28 of the pieces 11^b and 11^a respectively, are rounded as at 29 to provide a curved backing for the flexible disc 22 when the latter is bent backwardly as against the inner piece 11^a, or forwardly as against the outer piece 11^b, when the carrier is traveling in one direction or the other, it being understood that the flexible washer is of slightly larger diameter than that of the transit tubes and will be flexed in one direction or the other by the walls of the tubes depending upon the direction of flight of the carrier therethrough. The rounded corners at the meeting surfaces of the pieces 11^a and 11^b provide an annular recess which permits this flexure of the washer to take place while at the same time providing the proper amount of stiffening or backing after the bending of the washer an amount sufficient to curve it over the rounded corners, which action results in insuring a tight connection between the washer and the walls of the tubes.

The wear on the buffer head is taken up almost entirely by the outer piece 11^b thereof, the inner piece 11^a remaining intact and in good condition for an indefinite time. When it becomes necessary therefore to replace a worn buffer head it is unnecessary to substitute an entirely new head as is now the practice where the buffer consists of a single piece of felt. Instead, the buffer head may be restored to its primary state of usefulness and efficiency simply by removing the upper piece 11^b, and since the latter comprises only about 50% of the material in the entire buffer head a substantial saving is effected in the cost of material. Furthermore, the bearing plate or disc 22 and the screws 24 entering the sockets 17 in the screws 13 provide

quick detachable means for fastening the outer piece 11^b in position, thus effecting a saving in time and labor and consequently in the cost of replacements over the cost where single piece buffer heads are used. 70 The removal of the outer piece 11^b is readily accomplished simply by prying open the wire clips 30 holding the numbering device in place, where the buffer head is provided with the latter, removing the discs 26 and 75 25 and unscrewing the screws 24 which is an extremely simple operation and may be quickly performed.

I claim:

1. A carrier for pneumatic dispatch tube 80 systems having a buffer head at its end, said buffer head consisting of a plurality of separate circular pieces of resilient material arranged end to end in superimposed relation, said pieces being of substantially the same 85 diameter and separately detachable one from the other and from the carrier shell.

2. A carrier for pneumatic dispatch tube 90 systems having a buffer head at its end, said buffer head consisting of a plurality of separate pieces arranged in superimposed relation and separately detachable one from the other and from the carrier shell, and a flexible washer of larger diameter than said buffer head interposed between two of said 95 pieces.

3. A carrier for pneumatic dispatch tube 100 systems having a buffer head at its end, said buffer head consisting of a plurality of separate pieces arranged in superimposed relation and separately detachable one from the other and from the carrier shell, and a flexible 105 washer of larger diameter than said buffer head interposed between two of said pieces, the opposing faces of the latter having rounded peripheral edges to provide a curved backing for said washer when bent forwardly or backwardly depending upon the direction of travel of the carrier.

4. A carrier for pneumatic dispatch tube 110 systems having a two-piece buffer head of resilient material consisting of an inner piece secured to the carrier shell and a quick detachable outer piece superimposed upon said inner piece, the said two pieces being of resilient material, circular in form, and having substantially the same diameter. 115

5. A carrier for pneumatic dispatch tube 120 systems having a two-piece buffer head consisting of an inner piece secured to the carrier shell, a quick-detachable outer piece superimposed upon said inner piece, and a flexible washer of larger diameter than the buffer head interposed between said pieces. 125

6. A carrier for pneumatic dispatch tube 130 systems having a two-piece buffer head consisting of an inner piece secured to the carrier shell, and a quick-detachable outer piece superimposed upon said inner piece, said pieces being of larger diameter than

- the shell of the carrier, and a flexible washer of larger diameter than the buffer head which is interposed between the pieces comprising the latter.
5. 7. A carrier for pneumatic dispatch tube systems having a two-piece buffer head consisting of an inner piece secured to the carrier shell, and a quick-detachable outer piece superimposed upon said inner piece, 10 said pieces being of larger diameter than the shell of the carrier, and a flexible washer of larger diameter than the buffer head interposed between the pieces comprising the latter, the opposing faces of said pieces having rounded outer peripheral edges to provide a curved backing for said washer when bent forwardly or backwardly depending upon the direction of travel of the carrier.
8. A carrier for pneumatic dispatch tube 20 systems having a two-piece buffer head consisting of a circular inner piece and a circular outer piece superimposed upon said inner piece and of substantially the same diameter, devices for securing said inner piece 25 to the shell of the carrier, and means for fastening the outer piece upon said devices.
9. A carrier for pneumatic dispatch tube systems having a two-piece buffer head con-
- sisting of an inner piece and an outer piece, 30 and a screw member for securing said inner piece to the carrier shell having a shank portion provided with a threaded socket, said outer piece being provided with means for fastening it in superimposed relation to the inner piece whereby said outer piece may 35 be quickly detached from the carrier, said fastening means comprising a screw passing through said outer piece and which is adapted to enter said threaded socket.
10. A carrier for pneumatic dispatch tube 40 systems having a two-piece buffer head consisting of an inner piece and an outer piece, and screw members passing through said inner piece and having nuts on the inside of the shell for securing said inner piece there- 45 to, each of said screw members having a shank portion provided with a threaded socket, and said outer piece being provided with means for fastening it in superimposed relation to the inner piece whereby the outer 50 piece may be quickly detached from the carrier, said fastening means comprising a screw passing through said outer piece and adapted to enter said threaded sockets.

In testimony whereof I affix my signature.
ERNEST R. GIPPERT.
